MINING APPARATUS

Filed Feb. 7, 1929

Fig. 1.

UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING APPARATUS

Application filed February 7, 1929. Serial No. 338,286.

This invention relates to mining apparatus and more particularly, but not exclusively, pertains to coal mining apparatus of the wheel mounted bottom cutter type adapted to operate from the mine trackway.

An object of this invention is to provide an improved coal mining apparatus of the wheel mounted bottom cutter type having a pivotally mounted cutter bar and improved means for adjusting and swinging the cutter bar whereby the bottom of the kerf cut thereby may form a continuation of the plane of the mine bottom. Another object is to provide in a mining apparatus of the aforesaid type improved automatic bar swinging means whereby the angle of the cutter bar relative to its pivotal support is changed automatically as the cutter bar is swung from one side of the mine trackway to the other. A further object is to provide an improved bottom cutting coal mining machine of the pivoted cutter bar type having an improved adjustable pivotal mounting whereby the pivotal axis of the cutter bar may be positioned outside the mine trackway to enable the bar to cut on the mine bottom and also including means for changing automatically the angle of the cutter bar relative to its pivotal mounting as the cutter bar is swung transversely across the end of the trackway. Yet another object is to provide improved means in a mining apparatus of the aforesaid type whereby the cutter bar, as the same is moved transversely across the end of the mine trackway, may automatically assume various positions and move gradually through the angle necessary to bring the cutter bar into these positions so that the cutter bar is disposed at opposite angles at opposite sides of the trackway. These and other objects and advantages of this invention will, however, hereinafter more fully appear.

In the accompanying drawing there is shown for purposes of illustration one embodiment which the invention may assume in practice.

Fig. 1 is a top plan view of the improved mining apparatus.

Fig. 2 is a side elevational view, partially shown in section to illustrate details of con-

struction, of the mining apparatus shown in Fig. 1.

Fig. 3 is a diagrammatic view showing the mining apparatus during its transverse cutting operation.

In this illustrative form of the invention the same is shown embodied in a coal mining apparatus of the same general type as that disclosed in my copending application, Serial No. 199,053, filed October 29, 1917, and having incorporated therewith the plural speed truck wheel drive of the Levin Patent 1,565,376 and generally comprising a truck frame 1 mounted on wheels 2 adapted to run along a mine trackway 3 and having mounted thereon improved adjustable kerf cutting mechanism generally designated 4. Mounted on the truck frame 1 and having vertical adjustability relative thereto is a support 5 herein comprising an annular frame on which a swivel support or turntable 6 is mounted for rotative movement about a vertical axis. The vertical adjusting means herein comprises vertical rotatable screws 7 supported by upstanding brackets carried by the truck frame and having cooperating therewith non-rotatable nuts 8 carried by depending brackets suitably secured to the annular swivel supporting frame 5, the screws being rotated from a motor 9 on the truck frame through connections similar to those described in the above mentioned patent and including an endless chain 10 engaging and driving chain sprockets 11 suitably secured to the lower ends of the rotatable adjusting screws 7. As is also described in the above mentioned patent, the motor 9 drives through a friction controlled plural speed transmission mechanism generally designated 12 the truck wheels 2. This truck wheel driving mechanism includes chain and sprocket connections 13 and 14 connected to the truck wheel axles. This plural speed transmission mechanism is adapted to effect drive of the truck wheels to propel the apparatus bodily along the mine trackway comparatively slowly during cutting and at a relatively high transport speed, as is described in the above mentioned patent. As these driving connections for the turntable

adjusting means and the driving means for the truck wheels do not specifically enter into this invention, further description of the same is considered to be unnecessary.

5 The kerf cutting mechanism 4 and the driving mechanism therefor herein comprises a motor 15 supported on the turntable 6 and suspended therefrom beneath the same. As illustrated, this motor 15 has secured to its power shaft 16 a spur pinion 17 which meshes with a spur gear 18 fixed to a horizontal shaft 19. Secured to the inner end of the shaft 19 is a bevel pinion 20 meshing with a bevel gear 21 suitably fixed to the 15 lower end of a vertical shaft 22 having its axis arranged coincident with the turntable axis. As shown in Fig. 2 of the drawing, the shaft 22 has suitably fixed thereto at its upper end a chain sprocket 23 connected by an 20 endless chain connection 24 to a chain sprocket 25 rigidly fixed to the upper end of a vertical drive shaft 26. In this instance the shaft 26 is journaled in bearing sleeves carried by a tubular pivotal support 27 in turn 25 journaled within a tubular bearing support 28 carried on the outer end of and depending from an arm-like frame or bracket 29 secured to and projecting laterally from the swivel support 6. Carried by the lower end 30 of the tubular bearing support 27 is a bracket 30 carrying an elongated plane cutter bar 31 about the outer edges of which a usual endless cutter bit carrying cutter chain 32 is orbitally movable. The endless cutter chain 32 engages and is driven by a chain sprocket 33 suitably fixed to the lower end of the vertical drive shaft 26. Any suitable clutch mechanism 34 may be employed for connecting the spur gear 18 to or disconnecting the same from the shaft 19 thereby permitting the cutter chain 32 to be driven by the motor at will or for disconnecting the same therefrom while the motor continuously rotates.

Mechanism is provided for rotating the 45 swivel support or turntable 6 relative to the supporting frame 5 and herein comprises an eccentric member 35 suitably secured to the vertical shaft 22 and suitably connected by an arm 36 to a pawl 37 which engages the 50 teeth on a usual ratchet wheel 38. Through this ratchet mechanism intermittent rotation is transmitted from the motor to a horizontal shaft 39 suitably geared to a horizontal clutch controlled winding drum 40 rotatably mounted about a vertical axis on the swivel frame 6, the gearing between the shaft 39 and the winding drum and the controlling clutch for the drum being of a type similar to that disclosed in the above mentioned patent to Levin. 55 Wound upon the drum 40 is a cable 41 which is adapted to be reeved about a plurality of horizontal guide sheaves 42 journaled on the swivel frame and the free end of this cable is connectible as at 43 to an abutment member 60 suitably secured to the supporting frame

5. Usual pivoted latch mechanism 44 is provided engageable with a plurality of notches 45 formed on the outer edge of the swivel frame 6 for locking the latter to the frame 5 in its different adjusted positions about its 70 pivotal axis. It will thus be seen that when the winding drum 40 is connected to the motor through the above described ratchet and pawl mechanism the drum may be slowly rotated to wind in the cable 41 and as a result 75 the swivel frame 6 is slowly rotated relative to the supporting frame 5.

The improved mechanism for changing automatically the angle of the cutter bar relative to its pivotal support as the cutter bar is swung transversely across the end of the mine trackway herein comprises a stationary spur gear or arcuate rack 46 arranged coaxially with the vertical shaft 22 and having its depending hub portion suitably rigidly fixed to a radial arm or bracket 47 suitably secured as by screws to the relatively stationary frame member 5. As illustrated, meshing with the stationary spur gear or rack 46 is a spur gear 48 journaled on a vertical stud projecting upwardly from the swivel frame 6, the spur gear 48 being rotatable about a vertical axis arranged parallel with and in advance of the axial line of the swivel frame or turntable 6. Meshing with the spur gear 48 is a gear segment 49 supported on a sleeve 50 carried by the bracket 29, this gear segment being swingable about the pivotal axis of the cutter bar. It will be noted that as the cutter bar is swung transversely in its plane from the full line position shown in Fig. 1 to the full line position shown in Fig. 3, the angle of the cutter bar relative to the pivotal support therefor is changed automatically, the gear 48 meshing with the stationary gear 46 rotating as the swivel support 6 is rotated about its pivot and as a result the gear segment 49 meshing with the gear 48 is swung, moving therewith the cutter bar. As shown in Fig. 2, splined at 51 for axial sliding movement on the upper end of the tubular bearing support 27 for the cutter bar is a clutch member 52 having clutch teeth 53 engageable with clutch teeth 54 on the hub of the gear segment 49. This clutch member is provided with suitable shifting means including a pivoted yoke 55 having a suitable operating handle 56. It will thus be seen that the clutch member 52 may be moved upwardly from the position shown in Fig. 2, to thereby release the cutter bar from the gear segment 49 in such manner as to permit free swinging movement of the cutter bar relative to the gear segment for purposes to be later described.

The operation of the improved mining apparatus is as follows. The apparatus is propelled forwardly about the mine at a fast speed by the motor 9 through the transmis-

sion mechanism 12, the motor 9 being reversed when it is desired to propel the apparatus rearwardly along the mine trackway. When the working face is reached the 5 operator starts the motor 15 and the winding drum 40 is suitably connected to the motor and the cable 41 so arranged that when the drum 40 is rotated to wind in the cable the swivel support 6 is swung about its pivotal axis to bring the pivotal axis of the cutter bar 31 into a position outside the mine trackway in a manner clearly described in 10 my copending application mentioned above. The cutter bar is then lowered to the bottom 15 of the mine through the adjusting mechanism 7, 8 for the swivel support 6. When the cutter bar assumes a position with its pivotal axis at one side of the mine trackway and the cutter bar is disposed on the mine bottom 20 in the dotted line position indicated at A in Fig. 3, the apparatus is moved longitudinally along the mine trackway comparatively slowly thereby sumping the cutter bar beneath the coal to the full line position indicated at B in that figure. After the sumping 25 cut has been completed, the cable 41 is arranged as indicated in Fig. 1 and upon rotation of the winding drum 40 the cable is drawn in and the swivel support 6 for the 30 cutter bar 31 is swung about its axis, thereby moving the cutter bar transversely in its plane across the end of the mine trackway from the full line position B in Fig. 3 to the dotted line position indicated at C in that 35 figure. As the cutter bar is swung transversely across the face the meshing engagement of the gears 46, 48, and 49 causes the cutter bar to be automatically angled relative to its pivotal support, the axes of the 40 turn table, bar pivot, and the longitudinal axis of the cutter bar lying in the same straight line as the parts assume their intermediate position and the cutter bar thereafter being angled in the opposite direction 45 as the parts approach the dotted line position C shown in Fig. 3. After the transverse cut has been completed, the apparatus is moved bodily rearwardly along the mine trackway to withdraw the cutter bar from 50 the coal to the position indicated at D in Fig. 3. The cutter bar thereafter is elevated from the mine bottom and returned to its central transport position as indicated in full lines in Fig. 1. It will be evident that if it 55 is desired to swing the cutter bar relative to the automatic bar swinging mechanism it is only necessary to release the clutch 52 thereby disconnecting the bar support 27 from the gear segment 49, it being possible 60 by releasing this clutch to vary the initial angular position of the cutter bar relative to the swivel support. These and other operations of the improved mining apparatus will be clearly apparent to those skilled in 65 the art.

As a result of this invention it will be noted that an improved coal mining apparatus is provided having an improved adjustable pivotal support for the cutter bar whereby the latter may be positioned on the 70 mine bottom outside the mine trackway. It will further be noted that an improved bar swinging and positioning mechanism is provided whereby the angle of the cutter bar relative to its pivotal support is changed 75 automatically as the cutter bar is swung transversely in its plane across the end of the mine trackway. It will still further be noted that an improved automatic bar swinging mechanism is provided which is of 80 an exceedingly simple and rugged character readily adapted to be applied to a mining apparatus of standard design and construction, and which is especially adapted to withstand the severe conditions of service 85 encountered in mines.

While there is in this application specifically described one form which the invention may assume in practice, it will be understood that this form of the same is shown 90 for purposes of illustration and that this invention may be modified and embodied in various other forms without departing from its spirit or the scope of the appended claims.

What I claim as new and desire to secure 95 by Letters Patent is:

1. In a mining apparatus, the combination of a support, a second support mounted on said first support for rotation upon a vertical axis, kerf cutting mechanism supported 100 entirely by said first support during the cutting operation and including a cutter bar pivotally mounted on said second support for swinging movement in its plane of cutting upon an axis parallel to the axis of rotation of said second support, self-contained power operated means solely supported by said supports for effecting rotation of said second support upon its axis of rotation to effect 105 swinging movement of said cutter bar about the axis of rotation of said support at a cutting speed to cause said bar to effect its swinging cut, means operatively connected to said supports and said cutter bar for swinging automatically said cutter bar upon its 110 own pivotal axis relative to said second support as said second support is rotated, said automatic bar swinging means including transmission connections operatively connected to a stationary element on said first support and to said cutter bar, and self-contained power operated means solely supported by said first support for moving the apparatus bodily in opposite directions at a 115 cutting speed to effect sumping and withdrawal movements of said cutter bar.
2. In a mining apparatus, the combination of a support, a second support mounted on said first support for rotation upon a vertical axis, kerf cutting mechanism includ- 120
- 125
- 130

ing a cutter bar pivotally mounted on said second support for swinging movement upon an axis parallel to the axis of rotation of said second support, means for effecting rotation of said second support upon its axis of rotation to effect swinging movement of said cutter bar about the axis of rotation of said second support, and means operatively connected to said supports and said cutter bar for swinging automatically said cutter bar upon its own pivotal axis relative to said second support as said second support is rotated, said automatic bar swinging means including a gear member secured to said first support, a rotatable gear carried by said second support and meshing with said gear member, and a gear member connected to said cutter bar and meshing with said gear.

20 3. In a mining apparatus, the combination of a support, a second support mounted thereon for rotation upon a vertical axis, kerf cutting mechanism supported entirely by said first support during the cutting operation and including a cutter bar pivotally mounted on said second support for swinging movement upon an axis parallel to the axis of rotation of said second support, self-contained power operated means solely supported by said supports for effecting rotation of said second support upon its axis of rotation to effect swinging movement of said cutter bar about the axis of rotation of said support at a cutting speed to cause said bar to effect its swinging cut and including a motor and mechanism driven thereby carried by said second support and rotatable therewith, means operatively connected to said supports and said cutter bar for swinging automatically said cutter bar upon its own axis relative to said second supports as said second support is rotated, and self-contained power operated means solely supported by said first support for moving the apparatus bodily in opposite directions at a cutting speed to effect sumping and withdrawal movements of said cutter bar.

40 4. In a mining apparatus, a wheeled support movable along a mine trackway, a second support mounted on said first support for rotation upon a vertical axis, kerf cutting mechanism on said second support and supported entirely by said wheeled support during the cutting operation and including a pivoted cutter bar mounted for swinging movement relative to said second support upon an axis parallel with the axis of rotation of said second support, self-contained power operated means solely supported by said supports for effecting rotation of said second support relative to said first support to effect positioning of said bar pivot outside the trackway with said cutter bar disposed to cut a kerf at the level of the mine bottom and for swinging said cutter bar across the end of the trackway at a cutting speed to effect its swinging cut, means for swinging automatically said cutter bar upon its own pivotal axis relative to said second support as said second support is rotated to effect swinging movement of said cutter bar across the end of the trackway, and self-contained power operated means solely supported by said wheeled support for driving the support wheels to propel the apparatus bodily along the mine trackway in opposite directions at a cutting speed to effect sumping and withdrawal movements of said cutter bar.

60 5. In a mining apparatus, a wheeled support movable along a mine trackway, a second support mounted on said first support for rotation upon a vertical axis, kerf cutting mechanism on said second support and supported entirely by said wheeled support during the cutting operation and including a cutter bar pivotally mounted on said second support for swinging movement upon an axis parallel to the axis of rotation of said second support, means for effecting rotation of said second support upon its axis to effect swinging movement of said cutter bar about the axis of said second support, and means operatively connected to said supports and said cutter bar for swinging automatical-

across the end of the trackway at a cutting speed to effect its swinging cut, means for swinging automatically said cutter bar upon its own pivotal axis relative to said second support as said second support is rotated to effect swinging movement of said cutter bar across the end of the trackway, said automatic bar swinging means including transmission connections operatively connected to a stationary element of said first support and to said cutter bar, and self-contained power operated means solely supported by said wheeled support for driving the support wheels to propel the apparatus bodily along the mine trackway in opposite directions at a cutting speed to effect sumping and withdrawal movements of said cutter bar.

85 5. In a mining apparatus, a wheeled support movable along a mine trackway, a second support mounted on said first support for rotation upon a vertical axis, kerf cutting mechanism on said second support and entirely supported by said wheeled support during the cutting operation and including a pivoted cutter bar mounted for swinging movement relative to said second support upon an axis parallel with the axis of rotation of said second support, self-contained power operated means solely supported by said supports and including a motor and connections driven thereby carried by said second support and rotatable therewith for effecting rotation of said second support relative to said first support to effect positioning of said bar pivot outside the trackway with said cutter bar disposed to cut a kerf at the level of the mine bottom and for swinging said cutter bar across the end of the trackway at a cutting speed to effect its swinging cut, means for swinging automatically said cutter bar upon its own pivotal axis relative to said second support as said second support is rotated to effect swinging movement of said cutter bar across the end of the trackway, and self-contained power operated means solely supported by said wheeled support for driving the support wheels to propel the apparatus bodily along the mine trackway in opposite directions at a cutting speed to effect sumping and withdrawal movements of said cutter bar.

100 6. In a mining apparatus, the combination of a support, a second support mounted on said first support for rotation about a vertical axis, kerf cutting mechanism including a cutter bar pivotally mounted on said second support for swinging movement upon an axis parallel to the axis of rotation of said second support, means for effecting rotation of said second support upon its axis to effect swinging movement of said cutter bar about the axis of said second support, and means operatively connected to said supports and said cutter bar for swinging automatical-

ly said cutter bar upon its own pivotal axis relative to said second support as said second support is rotated, said automatic bar swinging means including intermeshing gearing connecting said cutter bar and said first support and said gearing effecting swinging of said cutter bar upon its pivot as said second support is rotated.

7. In a mining apparatus, the combination 10 of a support, a second support mounted on said first support for rotation upon a vertical axis, kerf cutting mechanism supported by said first support and including a cutter bar pivotally mounted on said second support for swinging movement in its plane of cutting upon an axis parallel to the axis of rotation of said second support, power operated means for effecting rotation of said second support upon its axis to effect swinging 20 movement of said cutter bar about the axis of rotation of said second support at a cutting speed to cause said bar to effect its swinging cut, means operatively connected to said supports and said cutter bar for swinging 25 automatically said cutter bar upon its own pivotal axis relative to said second support as said second support is rotated, said automatic bar swinging means including transmission connections operatively connected to 30 a stationary element on said support and to said cutter bar, and power operated means for moving the apparatus bodily in opposite directions at a cutting speed 35 to effect sumping and withdrawal movements of said cutter bar.

8. In a mining apparatus, a wheeled support movable along a mine trackway, a second support mounted on said first support for rotation upon a vertical axis, kerf cutting mechanism mounted on said second support and including a pivoted cutter bar mounted for swinging movement relative to said second support upon an axis parallel with the axis of rotation of said second support, power operated means for effecting rotation of said second support relative to said first support to effect positioning of said bar pivot outside the trackway with said cutter bar disposed to cut a kerf at the level of the mine bottom and for swinging said cutter bar across the end of the trackway at a cutting speed to effect its swinging cut, means for swinging automatically said cutter bar upon its own pivotal axis relative to said second support as said second support is rotated to effect swinging movement of said cutter bar across the end of the trackway, said automatic bar swinging means including transmission connections operatively connected to a stationary element of said first support and to said cutter bar, and power operated means for driving the support wheels to propel the apparatus bodily along the mine trackway in opposite directions at a cutting speed to ef-

fect sumping and withdrawal movements of said cutter bar.

9. In a mining apparatus, a wheeled support movable along a mine trackway, a second support mounted on said first support for rotation upon a vertical axis, kerf cutting mechanism on said second support and including a pivoted cutter bar mounted for swinging movement relative to said second support upon an axis parallel to the axis of rotation of said second support, power operated means including a motor and connections driven thereby carried by said second support and rotatable therewith for effecting rotation of said second support relative to said first support to effect positioning of said bar pivot outside the trackway with said cutter bar disposed to cut a kerf at the level of the mine bottom and for swinging said cutter bar across the end of the trackway at a cutting speed to effect its swinging cut, means for swinging automatically said cutter bar upon its own pivotal axis relative to said second support as said second support is rotated to effect swinging movement of said cutter bar across the end of the trackway, and power operated means for driving the support wheels to propel the apparatus bodily along the mine trackway in opposite directions at a cutting speed to effect sumping and withdrawal movements of said cutter bar.

In testimony whereof I affix my signature.
MORRIS P. HOLMES.
